C. R. HARDY,
LIGHTING FIXTURE,
APPLICATION FILED JAN. 26, 1917.

1,284,324.

Patented Nov. 12, 1918.

CHARLES R. HARDY,
INVENTOR.

BY *William A. Hirtle,*
ATTORNEY.

UNITED STATES PATENT OFFICE.

CHARLES R. HARDY, OF WILKINSBURG, PENNSYLVANIA.

LIGHTING-FIXTURE.

1,284,324.

Specification of Letters Patent. Patented Nov. 12, 1918.

Application filed January 26, 1917. Serial No. 144,644.

To all whom it may concern:

Be it known that I, CHARLES R. HARDY, a citizen of the United States of America, residing at Wilkinsburg, in the county of 5 Allegheny and State of Pennsylvania, have invented certain new and useful Improvements in Lighting-Fixtures, of which the following is a specification.

The present invention relates to lighting 10 fixtures, and more particularly to that type of fixtures known as "drop lights" and capable of being lowered and raised with relation to the point of support, and is designed to replace the ordinary gas or 15 electric light table lamp and its accompanying cord containing the flexible gas tube or electric wires. My lighting fixture can be conveniently attached to a chandelier or directly connected to a ceiling support as will 20 be explained hereinafter in this specification.

My invention has a valuable feature in 25 that it may be used with slight modifications for gas or electric light, or both in combination and means is provided whereby it can be readily raised or lowered in a vertical line, thereby making a smoothly operating "drop light" fixture, and one which has no counter-weight or other like objectionable 30 features. Its construction enables it to be placed in any number of desired positions of elevation, and it can be entirely raised in position when not in use where it does not form an obstruction.

35 In the accompanying drawing I have shown one complete example of the physical embodiment of my invention constructed according to the best mode I have so far devised for the practical application of the 40 principles of my invention.

Figure 1 is a front view of my invention.

Fig. 2 is a vertical central sectional view taken from the right of Fig. 1.

Fig. 3 is a cross-sectional view taken on 45 line 3—3 of Fig. 1.

Fig. 4 is an enlarged partial section showing the interior construction of a portion of Fig. 3, and taken on line 4—4 of Fig. 1.

Fig. 5 is a cross sectional view on line 50 5—5 of Fig. 4, of a portion of the device.

Fig. 6 is an end view taken on line 6—6 of Fig. 4.

Fig. 7 is a front view of one of the washers used with my device.

55 Fig. 8 is a cross-sectional view taken on line 8—8 of Fig. 1.

Fig. 9 is a side view of a joint of my invention partly in section and taken looking in the direction of the arrows of line 9—9 of Fig. 1.

Fig. 10 is a cross-sectional view of a part of the device taken on line 10—10 of Fig. 9.

The numeral 1 is a casting having a threaded end 2 and a central interior duct or passage 3, with a branch passage 4, and another branch passage 5. Passages 4 and 5 are separated one from the other by a division wall 6. Passage 5 has an aperture 7 which communicates with the outside as shown in Fig. 8. It will be noted that I 70 have shown the threaded end 8 dotted and same is for attachment of the casting 1 under conditions where the supply line is from a point overhead, as in the ceiling of a room in a building, while the end 2 is suitable for attachment to a side wall or a side connection to a chandelier or a like support. 75

Two meshing arc gear castings 9, 10 having projections 11, 12 like a frustum of a cone in shape are adapted to rotate in 80 sockets 13, 14 formed therefor in the casting 1. The arc gear castings 9, 10 have central passages 15, 16 which communicate with passages 4 and 5 of casting 1 and with passages 17, 18. The left side of the device 85 19 is for use as a gas supply line to point 21, while the right side 20 is for the wires leading to the electric light socket 22, but the uses of each may be reversed if the construction of the parts is correspondingly 90 changed. In the part 11, a circumferential slot or groove 23 and an entrance duct 24 keeps passage 4 in constant communication with aperture 17 when 11 is revolved in socket 13 as is readily understood. In the 95 part 12 half of the material as seen in the similar cross-section in Fig. 5, is cut away at 25 in order that the leading-in wires 26 may have space in which to reside when the part 12 is rotated in its socket 14.

Following the "gas" side 19 of the fixture, 100 27 is a pipe screwthreaded into arc gear casting 9, and also into a casting 28 of ordinary construction in the art, and a casting 29 also of usual construction is adapted to rotate in casting 28, and communicating passages which are continuously open lead therethrough from aperture 17, through pipe 27, castings 28, 29 into pipe 30. The pipe 30 is threaded into casting 29, and also threaded 105 into arc gear casting 31. The casting 32 is very similar in construction to the support- 110

ing casting 1 before described, and has a passage 33 which is in communication with the interior duct of pipe 34, the latter being screwthreaded into casting 32, as shown, and 5 gas is intended to be conveyed from pipe 30 through casting 32 by means of ducts 35, 36 into pipe 34. It will be noted that passages 35, 36 are continuously in communication with each other in similar fashion to the construction indicated by 11 and ducts 4 and 24 as is shown in Figs. 2 and 3. The casting 32 also has a duct 37 which communicates with passage 38 of the arc gear casting 39, and aperture 40 of same. The section shown in 10 Fig. 5 illustrates that the portion 25 of the part 41, being cut away as indicated, enables the part 41 to be rotated in socket 42, of the casting 32, and the electric wires 26 may thus have space in which to reside during 15 the revolution of 41. The passage 37 is separated from the gas duct 33, by a division wall 84, as shown and a raised or bossed portion 43 is formed in the body of casting 32 with a passage 44 therethrough, and through 20 which the electric wires 26 are led into passage 46 of the pipe 47. The inner pipe 34 leads the gas obtained from aperture 33 into a casting 48, and is screwthreaded into same as shown, and into 32 as before stated. The 25 casting 48 has a passage 49 therein which leads to the bore of the pipe 50 attached to said casting. The usual valve 51 and means of control 52, and attachment means 53 for a gas burner (not shown) is fastened on the 30 end of pipe 50, and thereby the gas is led from the point of entrance 54 in casting 1 to point 21 and to the burner. It is observed also that the movement of any of the aforesaid joints does not interfere with the continuous 35 flow of gas in any way, the only point of control between points 54 and 21 being part 52 and valve 51.

With reference to the "electric" side of the device 20, I have shown above that wires can be admitted to passage 5 through aperture 7, and therefrom to and through passage 16, and aperture 18. A pipe 55 is screwthreaded into the arc gear casting 10, and into casting 56, and through which the lead wires 26 40 from aperture 18, are led to and through a casting 57, and into pipe 58 as will be described. The casting 57 has a passage 59, positioned centrally thereof see Figs. 9, 10, and also a circumferential groove 60. The 45 passage 59 leads through aperture 61 into groove 60, as shown. The casting 56 has a passage 62 which registers with the groove 60 and the passage in the pipe 55. It is seen from the aforesaid figures that the electric 50 wires may be led from 55, through 62, around the groove 60, into aperture 61, and thence through 59 into pipe 58. It is further seen that any rotation of casting 57 in its socket 63, will merely tend to push wires 55 backward or forward in pipe 55, and the

interior bore 64, of said pipe is made of sufficient diameter to permit of the slight accumulation of wire and accommodate the partial rotation of casting 57 in socket 63, as will be further explained. The rotation of 70 57 in 63 I have illustrated in Fig. 10, in which 26, 65, 66, 67, 68 indicate the wires 26 in one position, when the device as a whole is in raised position shown by the full lines in Figs. 1, 2, while 69, 66, 67, 70, indicate the 75 wires when the fixture is in the lowered position, or that shown by the dotted lines in Fig. 1. It is seen that the effect of lowering the device is merely to shorten the portion 65 of wire 26 shown in Fig. 10, the surplus 80 of wire merely accumulating in pipe 55, as is readily appreciated.

As before stated the wires having been advanced to and within the pipe 58, are led through casting 32 as explained above in 85 connection with the description of said casting, and through the apertures 44 into the bore 46 of pipe 47, thence into the passage 71 in casting 48, and to the electric light socket 22. For convenience the electric light which 90 is attached to socket 22 is not shown. It will be noted that the pipe 47 is held in position by casting 48, and rests upon the top of same as shown clearly in Fig. 2.

In Figs. 6 and 7, I have shown the end of 95 part 41 as having a flattened side 72, and a washer 73 having a complementary aperture and adapted to be placed thereon, so that when part 41 is rotated in socket 42, the frictional surfaces where the rotation takes place 100 occurs between the washer 73, and the end 74 of part 41, otherwise the small screw 75 would be displaced by said rotation. The same means are used on the ends 76, 77, 78, 79, 80, 81 and for the same purpose. 105

The teeth of the arc gear castings 9 and 110 10 mesh with each other, and likewise the same is true of the teeth of castings 31 and 39, and the purpose of these intermeshing gears 9, 10, 31 and 39 is to enable the portion 82 carrying the electric light and the gas burner, to be raised and lowered in a truly vertical line, readily and smoothly, it having been found from experiment to accomplish this desirable result. 115

The fixture can be used wholly for gas instead of the combination fixture above described, in which case both branches 19, and 20, can be joined in so far as their interior passages are concerned and used for conveying the gas, the site 20 being made a counterpart of the side 19, small modifications being introduced as is readily seen to accomplish this purpose. The device can also be used as an electric light fixture where gas 120 is not desired. I have shown a portion 83, of the teeth of each of the arc gears filled in or uncut, the purpose being to restrict the final adjusting movement of the fixture vertically, at both its uppermost and lower- 125 130

most positions. It is also to be noted that the operation of the device in a truly vertical line as before stated, prevents any angular or bending strains being set up on the stem 5 of a chandelier to which the device may be attached, same being as is readily appreciated a very desirable feature of my invention.

What I claim is:—

- 10 1. In a combination gas and electric light fixture, a supporting casting comprising a centrally positioned portion having a pair of gas and electric wire ducts therethrough, an interior division wall formed in said casting, separating the said ducts from each other, a junction casting having a pair of gas and electric wire ducts therein, an interior division wall separating the said latter ducts, a hollow external boss formed on the 15 side of said junction casting accommodating the said electric wires, adjustable means provided with independent passages therethrough connecting the respective gas and wire ducts in the supporting and junction castings, and means for preventing injury to the electric wires in said connecting means, when the latter is adjusted in various 20 operable positions.
- 25 2. In a combination fixture for gas and electric light, a supporting casting having a pair of gas and electric wire ducts passing therethrough, an interior division wall between said ducts, formed in the said casting, a junction casting having a pair of gas and electric wire ducts therethrough, 30 an interior division wall in the latter casting separating the ducts in the same, adjustable connecting means provided with independent passages therethrough communicating with the respective gas and 35 wire ducts in the supporting and junction castings, an inner gas conveying pipe attached to the junction casting, an outer conduit for the electric wires surrounding the inner pipe, an abutment casting rigidly 40 mounted on the lower end of the inner pipe, provided with passages for independently carrying the gas, and electric wires therethrough to the respective light sources. 45

In testimony whereof I affix my signature 50 in the presence of two witnesses.

CHARLES R. HARDY.
